DESIGN FOR A DRESS OR SIMILAR ARTICLE

Jacob L. Honig, New York, N. Y.

Application October 7, 1939, Serial No. 87,557

Term of patent 3½ years

To all whom it may concern:

Be it known that Jacob L. Honig, a citizen of the United States of America and resident of New York, in the county of New York and State of New York, has invented a new, original, and ornamental Design for a Dress or Similar Article, of which the following is a specification, reference being had to the accompanying drawing, forming part thereof, in which,

Fig. 1 is a front view of a dress, or similar article, showing my new design; and

Fig. 2 is a rear view of the dress shown in Fig. 1.

The characteristic feature of my design resides in the combination on the dress disclosed of the specific blouse member having a notched front, a flaring peplum below the gathered waistline at the rear, and a round collar having a ruffled edge, with faggotting, in association with the full skirt, as shown.

I claim:

The ornamental design for a dress or similar article, substantially as shown and described.

JACOB L. HONIG.
